VACUUM BULK MILK TANK

George W. Crowther, Elyria, Ohio

Application July 8, 1958, Serial No. 51,695

Term of patent 14 years

(Cl. D23—1)

Fig. 1

The dominant features of the design reside in the portions shown in full lines.

I claim:

The ornamental design for a vacuum bulk milk tank, as shown and described.
